UNITED STATES PATENT OFFICE.

WARREN W. CARPENTER, OF BROOKLYN, NEW YORK, ASSIGNOR TO WESTERN ELECTRIC COMPANY, INCORPORATED, OF NEW YORK, N. Y., A CORPORATION OF NEW YORK.

MACHINE-SWITCHING TELEPHONE-EXCHANGE SYSTEM.

Application filed December 31, 1919. Serial No. 348,560.

To all whom it may concern:

Be it known that I, WARREN W. CARPENTER, a citizen of the United States, residing at Brooklyn, in the county of Kings, State

5 of New York, have invented certain new and useful Improvements in Machine-Switching Telephone-Exchange Systems, of which the following is a full, clear, concise, and exact description.

10 This invention relates to machine switching telephone exchange systems of the step-by-step type and more particularly to such systems involving a number of central offices.

15 Conditions on commercial trunk and subscribers' lines are such that a wide range of variation is encountered in the capacity, leak, length of line and voltage. This causes the impulse relay at each office, where the connection is built up over a number of

20 offices, to operate quickly and release slowly under certain of the above conditions, and to operate slowly and release quickly under other conditions. For example if the capacity, leak and voltage of a subscriber's

25 line or an inter-office trunk, which is a portion of the path over which a connection is being built up and which includes one of the impulse relays, are all low, and the trunk is long, the impulse relay will be slow to op-

30 erate and quick to release; on the other hand, if the capacity, leak and voltage are high and line or trunk is short, the impulse relay will be quick to operate and slow to release.

35 It will be readily seen that in a connection being built up over a number of inter-office trunks with an impulse relay in the repeating circuit at each office, the first relay directly in circuit with the finger wheel or

40 sender and the second impulse relay in circuit with a back contact of the first impulse relay and so on, that due to the variables mentioned, the impulse relays beyond the first in many cases would not transmit the

45 same number of impulses to the impulse relay or relays beyond as was transmitted by the finger wheel to the first impulse relay or the impulses would be so distorted as not to be effective to perform their function of

50 setting the switches properly. In some cases, the impulse relays farther along in the series would never get a chance to release; that is to say they would hold up over the breaks caused by the sender in the calling

line loop, resulting in the reduction of the 55 number of impulses of the particular set involved and the setting up of a wrong connection.

This invention provides a repeating arrangement which positively overcomes these 60 difficulties and permits of the use of any number of serially connected interoffice trunks in the same connection with an impulse relay at each office and wherein any selective switch, no matter how far along in 65 the chain of switches over which the call is progressing, being accurately set to the group determined by the particular digit of the wanted number with which such switch is involved, and wherein the adjustment of the sender, relays and apparatus 70 need not be as accurate as has heretofore been required.

In accordance with this invention, the circuit is so arranged that the set of impulses 75 which is operating a given impulse relay in the series corresponds in number to that set transmitted to the first impulse relay at the originating office, by the sender. However, the duration of each impulse transmitted to the stepping magnet at a given office 80 is independent of the duration of the corresponding impulse in the trunk caused by the impulse relay at the preceding office and is solely controlled by other factors which 85 are readily controllable to effect proper setting of the switches. The only requisite is that the impulse relay at a given office retract its armature momentarily a number of times corresponding to the interruptions 90 caused by the sender in the original circuit, and since this is only dependent upon variables in the particular trunk in which it is included, this requirement can be easily met.

The period of retraction of the armature 95 of the impulse relay in circuit with the sender does not determine the period during which the impulse relay at the next office and those beyond are deenergized but each impulse relay upon its retraction starts a 100 cycle of operations of a repeater at each office, the beginning and ending of which determines the duration of the break period of the impulse relay at the next office, this cycle of operations being entirely independent of 105 the period during which any impulse relay in the series is deenergized, but ending in each case before the associated impulse relay

again reaches its back contact due to the succeeding break in its circuit.

Referring to the drawings, Fig. 1, shows the calling subscriber's line, a line switch 5 and a first selector, the line switch brushes and multiples only, however, being shown; Fig. 2 shows an interoffice trunk circuit including a repeater; Fig. 3 shows an incoming selector at the distant office; Fig. 4 shows 10 a second selector; Fig. 5 shows a connector; Fig. 6 shows a private branch exchange connector; and Fig. 7 shows a trunk terminating before an operator which is one of a 15 first selector of Fig. 1.

Local calls.

Considering first a call between two subscribers in the same office, it is only necessary in a call of this character to consider 20 Figs. 1, 4 and 5 which should be placed in the order named from left to right. Upon the extension by the line switch L S of the calling line to an idle first selector, relay 25 101 thereof operates over the calling line circuit. Relay 101 operates show-release relay 102, over arms 113, (position 1) of the first selector sequence switch or side switch which relay in turn operates relay 103. Relay 30 102 also applies ground to the third wire 144 leading back to the line switch to maintain the same operated in the well-known manner. Relay 102 is locked up over a front contact of relay 103 to ground on 35 the lower front contact of relay 101, this circuit being independent of sequence switch arms 112 so that upon the subsequent movement of these arms, relay 102 and consequently relay 103 will be maintained operated. Relay 102 in closing its upper contact 40 completes a circuit over arm 110 including the sequence switch magnet 104 and its back contact which magnet thereupon advances the sequence switch to position 2, upon its 45 deenergization.

On the first interruption of the line circuit by the sender at the calling station in transmitting the impulses representing the 50 first digit of the wanted number, impulse relay 101 releases causing stepping relay 105 to operate by its right winding over a circuit including the uppermost grounded armature and front contact of relay 103, back contact of relay 101, arm 112 (position 55 2) left armature and back contact of relay 106 armature 181 and back contact of relay 109 and back contacts of magnets of 111 and 107. Relay 105 at its inner left armature closes a circuit for energizing relay 106 over its left winding and 60 left non-inductive winding of relay 105. The left-hand winding of relay 105 is merely a balancing resistance and has no magnetizing effect upon the relay. Relay 106 in attracting its left armature locks to ground 65

over arm 112 (position 2) the upper back contact of relay 101, and the uppermost front contact of relay 103. Relay 105 locks up to the lower grounded front contact of slow relay 102 over the armatures and back contacts of magnets 107, 111, its outer left armature and front contact, and arms 113 (position 2). At its right armature, relay 105 operates the primary magnet 107 over arm 118 (position 2) causing the first selector to take one primary step, on the completion of which the magnet 107 by opening its back contact interrupts the locking circuit of relay 105. Relay 105 releases, deenergizing the primary magnet. The locking circuit for relay 106 is opened when the impulse relay 101 again attracts its armature as the sender closes the line circuit at the calling station at the end of the first interruption provided relay 105 has released. 70 This completes the first cycle of operations, and upon each subsequent interruption of the line circuit by the sender at the calling station the same operations ensue. Relay 108 which like relay 102 is of the slow release type operates in circuit with the primary magnet 107 and is maintained energized during the transmission of the impulses, connecting the grounded third wire 144 to the sequence switch magnet 104, this circuit not 75 including the armature and back contact of the said magnet. When the impulses corresponding to the first digit of the wanted number have been transmitted, slow relay 108 releases, deenergizing magnet 104 which causes the sequence switch to advance to position 3. In position 3, relay 105 is operated from ground on the lower front contact of relay 101, over arms 113. Relay 109 is operated over arm 100 (position 3) closing a locking circuit for relay 105, including the armatures and back contacts of magnets 107 and 111, the outer left armature and front contact of relay 105, and armature 171 and front contact of relay 109. Relay 106 is energized by its left winding from ground at the inner left armature and front contact of relay 105. Contacts 3 and 4 of arm 110 are strapped together and connected to ground. The sequence switch on arriving in position 110 3 therefore is moved into position 4 over a circuit including magnet 104 and its armature and back contact and arm 110. Upon arriving in position 4 the sequence switch magnet 104 is held energized in a circuit independent of its self-interrupting contact as follows: magnet 104, conductor 153, arms 113 (position 4) conductor 154, right front contact of relay 106, to the grounded third wire 144. In position 4, relay 109 is still energized over arm 100. In position 4, relay 105 closes a circuit for secondary magnet 111 over arm 118, and the uppermost armature and front contact of relay 109 and causes the selector switch to take one secondary 115 120 125 130

step. The magnet 111 at the end of its stroke opens the locking circuit of relay 105 which thereupon releases. The test brush 145 of the first selector is now in engagement 5 with test multiple 146 of the first trunk which we shall assume is busy and therefore grounded. Relay 106 in such event finds a locking circuit which holds it operated, after relay 105 has released, over the noninductive 10 winding of relay 105 and its own left front contact, arm 112, (position 4) conductor 145 to ground on the test multiple 146. Relay 105 is operated again when the armature of primary magnet 111 reaches its back contact, 15 the circuit leading over the armatures and back contacts of the primary and secondary magnets 107 and 111, lowermost armature and front contact of relay 109, left armature and front contact of relay 106, arm 112 (position 20) to the grounded test terminal 146. Relay 105 in attracting its outer left armature locks itself to ground over armature 171 of relay 109. Relay 105 in operating transmits another impulse to secondary magnet 25 111 to advance the selector to the next trunk, its locking circuit being opened when the magnet 111 completes its stroke. Test brush 145 is now in engagement with the test multiple 146 of the second trunk and assuming 30 that this trunk is not busy it will not be grounded and relay 106 will release when relay 105 retracts its inner left armature due to its circuit being opened by the secondary magnet 111. Relay 106 in retracting its 35 right armature connects the grounded third wire 144 to the test brush 145 and thence to the multiples 146 of the seized trunk to render the same busy to other hunting first selectors. During the trunk hunting operation 40 relay 106 at its right front contact was maintaining sequence switch magnet 104 energized, this circuit leading from the grounded third wire by way of said right front contact, over conductor 144 and the arms 45 113 (position 4) conductor 153 to the sequence switch magnet 104, this circuit being independent of the armature and back contact of said magnet. On the release of relay 106 at the end of the trunk hunting operation 50 the sequence switch magnet 104 deenergizes advancing the sequence switch to position 5. Upon the retraction of the right armature of relay 106 and consequent extension of the grounded third wire to the third 55 wire 444 of the second selector, release relay 400 in the second selector circuit becomes energized over arm 402. Relay 400 in attracting its right armature closes a circuit for the sequence switch magnet 401 of the second selector, this circuit including arm 409 and the 60 armature and back contact of said sequence switch magnet, whereupon the second selector sequence switch is advanced by the magnet 401 to position 2. Relay 400 in position 2 locks itself over its left armature to the grounded third wire 444 through sequence switch arm 402. When the calling subscriber operates his sender to transmit the second digit of the wanted number, the first interruption of the line circuit, causes 70 impulse relay 101 at the first selector to release, operating stepping relay 105 thereat. The circuit is the same as previously described since contacts 1 and 5 of sequence switch arms 112 are strapped together. Relay 105 in turn operates relay 106 which locks itself through its left front contact to ground through arm 112 (position 5) and back contact of the line impulse relay 101. Relay 105, however, is now locked up over its outer 75 left armature and front contact, arms 113, (position 5) conductor 156 upper talking conductor, arms 403 of the second selector sequence switch (position 2) to ground at the armature and back contact of primary magnet 404 of the second selector. Relay 105 at its right armature closes a circuit through arm 118 (position 5) conductor 147, conductor 188, armature 155 and front contact of relay 103, lower talking conductor, arm 80 405 (position 2) of the second selector sequence switch through slow relay 406 to primary magnet 404. Magnet 404 is operated causing the second selector switch to take one step. Magnet 404 at the end of its stroke 85 unlocks relay 105 which in releasing releases magnet 404. When the line circuit is again closed by the sender at the end of the first interruption, relay 101 in attracting its upper armature unlocks relay 106 provided relay 105 has released. At the end of the series of impulses slow relay 406 releases. This relay is in circuit with the primary magnet 404 and has a similar function to slow relay 108 of the first selector. Relay 105 90 406 in releasing opens the circuit of sequence switch magnet 401 causing the second selector sequence switch to advance into position 3. Relay 407 is operated to ground over arms 403 (position 3) connecting this ground 95 at its left armature to the secondary magnet 408 of the second selector which rotates the test brush 413 into engagement with the test terminal 414 of the first trunk. The sequence switch advances from position 3 to 100 position 4 due to the permanent ground on the third contact of arm 409. Assuming that the first trunk is busy a circuit is closed from ground on the busy test terminal 414 over arm 410 (positions 3 and 4) to hold up relay 400 over its left front contact after its alternative circuit is opened by arm 402 passing out of position 3. The same ground causes relay 407 to operate over arms 403 105 (position 4). Relay 407 extends this ground to secondary magnet 408 which advances the selector switch to the next trunk. Assuming that this trunk is idle the test terminal 414 is therefore not connected to ground and relay 400 releases, connecting ground to se- 110

quence switch magnet 401 over arm 409 which advances the sequence switch into position 5. Arm 410 in position 5 grounds the test multiple of the seized trunk to render the 5 same busy.

In position 5, release relay 400 is again operated from ground on the third wire 444 over arm 402. In position 6 the upper and lower talking conductors of the first selector 10 are connected over the arms 403 and 405 to the connector. In position 5 arm 410 of the second selector closes a circuit including release relay 500 of the connector, which in turn operates sequence switch magnet 501 15 over a circuit including its inner right armature conductor 521 and arm 502, advancing the connector sequence switch to position 2. The calling subscriber now operates his sender to send the third digit of the wanted 20 number. Relays 101, 105 and 106 function in the manner described. The impulse from the relay 105 of the first selector passes over the path traced including arm 118 position 5, conductor 188 armature 155 to the lower 25 talking conductor to the primary magnet 503 of the connector which moves the connector one step and releases relay 105 on the completion of its stroke. Slow relay 504 operates in this circuit and connects the ground- 30 ed arm 505 (position 2) directly to the winding of the sequence switch magnet 501. Succeeding impulses cause the connector to be stepped to the desired group. At the end of the series of impulses, slow relay 504 re- 35 leases, causing sequence switch magnet 501 to deenergize which advances the sequence switch into position 3. The calling party now operates his sender to transmit the last digit of the wanted number. Secondary 40 magnet 506 is then operated in the same manner as described for magnet 503, magnet 506 being substituted for magnet 503 in the stepping circuit by arm 510. Upon the cessation of the impulses, slow relay 504 re- 45 leases, advancing the sequence switch to position 4. When the arm 502 moves off its third and onto its fourth contact a circuit is closed including the sequence switch magnet 501 and its armature and back contact. 50 Contacts 4 to 13 are strapped together and connected to ground. Consequently the sequence switch is advanced to position 14. While the sequence switch is advancing to position 14 the selected line is being tested. 55 If the line is busy, relay 500 is held up over its inner left armature in positions 5 and 6 of arm 507 to ground on the test terminal 514 of the busy line. The connection of the grounded third wire 544 to this relay is 60 opened as arm 520 leaves position 4. When the sequence switch reaches position 14, busy tone is connected by arm 509 to the upper talking conductor. While the connector sequence switch is advancing from positions 65 6 to 13, ground is connected over the inner

right armature and front contact of relay 500, conductor 521, arm 509, upper talking conductor to the first selector. Ground is also connected through the arm 510, lower talking conductor to the first selector causing magnet 104 of the first selector sequence switch to advance the sequence switch to position 6. This circuit leads from the lower talking conductor (Fig. 1) front contact and armature 155 of relay 103, conductors 188, 147, arm 118 (position 5), normal right contact of relay 105, arm 110 (position 5) to magnet 104. In position 6 this magnet is held up to the grounded lower talking conductor in a circuit including magnet 104, 75 conductors 153, 190 and arms 113. The ground over arm 509 of the connector sequence switch to the upper talking conductor operates ringing cutoff relay 133 at the 80 first selector, this circuit leading from the upper talking conductor (Fig. 1) over conductor 156 at the first selector armature 181 and front contact of relay 109, left back contact of relay 106, arm 112 (position 6) 85 right winding of relay 133 to battery. Relay 133 in attracting its inner right armature locks itself to the grounded third wire 144 over a back contact 192 of relay 148. When the connector sequence switch arm 510 moves out of its thirteenth position, the 90 circuit traced for the magnet 104 of the sequence switch of the first selector over the lower talking conductor is opened, whereupon the first selector sequence switch advances to position 7. This is the ringing 95 position, but since ringing cut off relay 133 is now operated, ringing cannot take place. In position 7, ground from the right outer front contact of relay 133, arms 118 and 110 causes sequence switch 104 to advance 100 the sequence switch magnet to position 8. In position 8 the talking circuits are connected from the calling subscriber to the connector due to the energization of relay 148, the circuit for this relay including the uppermost armature and front contact of 105 relay 103, arm 100 (position 8), arm 118, retracted right armature of relay 105, arm 110 (position 8) to battery through the sequence switch magnet 104. Magnet 104 is 110 marginal and does not operate in this circuit. The operation of the relay 148 extends the busy tone circuit including the upper talking conductor over its upper front contact to the calling subscriber's receiver through condenser 150, and a normal contact of relay 186 the return being over the lower talking conductor to battery through the lower winding of relay 101. 115

When the calling subscriber hangs up his receiver, relay 101 releases causing relays 102 and 103 to release in turn. The release of the uppermost armature of relay 103, removes ground from relay 148 which in re-tracting its armatures opens the connections 120 130

to the talking brushes of the first selector to prevent possible interference with established connections as the brushes wipe over the multiples. Ground from the lower back contact of relay 103 causes the release magnet 135 of the first selector to operate to restore the first selector to normal position. Upon reaching its normal position, off-normal contact springs 136 connect ground from the lowermost back contact of relay 103 over arm 110 (position 8) to sequence switch magnet 104 which advances the sequence switch to position 1. When the relay 101 releases and deenergizes relay 102, this relay by the retraction of its lower armature removes ground from third wire 144 which restores the line switch and also releases relay 400 of the second selector. Relay 400 in retracting its right armature closes a circuit including the contact springs 411, which are operated only on the eleventh rotary step of the selector over arm 409 (position 6), for sequence magnet 401. The second selector sequence switch thereupon moves from position 6 to position 15 over this circuit. When arm 409 reaches its fifteenth position it finds ground directly at the right armature and back contact of relay 400, whereupon the second selector sequence switch continues to advance to position 22. In position 22 ground on arms 403 operates release magnet 412 of the second selector, which restores the second selector to normal. Upon reaching its normal position this selector restores off-normal springs 413 which close a circuit including arm 409 to sequence switch magnet 401, advancing the sequence switch to position 1. When the second selector sequence switch arm 410 moved out of position 6 it removed ground from the third wire 544 of the connector switch causing relay 500 thereat to release. Ground from the inner right back contact of relay 500 and arm 502 (position 14) of sequence switch magnet 501 causes the connector sequence switch to advance to position 16. Relay 500 is operated in position 16 from ground on arm 505. The inner right front contact of relay 500 connects ground to the sequence switch magnet 501 over arm 502 (position 16) causing the sequence switch to advance into position 17. Relay 500 releases as arm 505 moves out of position 16 and its inner right back contact connects ground to the seventeenth to twenty-first contacts of arm 502, advancing sequence switch into position 22. Release magnet 512 is operated in position 22 over off normal springs 513 from ground on arm 505 causing the connector to return to normal. Upon restoration, the connector closes off-normal springs 513 which close a circuit for magnet 501 over arm 502 to advance sequence switch to normal.

Assuming now that the selected line had been idle. An idle condition is represented by an absence of ground on the test terminal 514. Relay 50 releases when the connector sequence switch advances into position 5 since the grounded third wire 544 is disconnected from relay 500 as arm 520 leaves position 4. While the connector sequence switch is advancing to position 13, ground is connected through the arm 510 and the lower talking conductor to the first selector as described causing the first selector sequence switch to advance to position 6 as on a busy connection. Due to the line being idle and consequently relay 500 being inert, no ground is present on the upper talking conductor at this time and consequently the relay 133 is not operated as it was in the case of a busy line. When the connector sequence switch advances into position 14 the first selector advances to position 7 as described in the case of a busy line. Due to relay 500 being inert the sequence switch moves out of positions 14 and 15 into position 16 over arm 502. In position 16 relay 500 energizes over arm 505, advancing the sequence switch out of position 16 and into position 17. In this position the talking conductors are connected through to the called line. The first selector sequence switch in position 7 connects ringing generator and ground to the called subscriber's line over the upper and lower conductors respectively. This circuit includes the left winding of relay 133, arms 113 (position 7) armature 155 and front contact of relay 103, lower talking conductor, the bell at the called station and returning over the upper talking conductor, conductors 156 and 160, front contact and armature 181 of relay 109, left armature and back contact of relay 106 to ground over 112 (position 7). When the called subscriber answers, the removal of his receiver closes an operating circuit for the ringing cut off relay 133, which locks itself over its right winding and its inner right armature and front contact, contact 192 of relay 148, to the grounded third wire 144. Relay 133 in attracting its outer right armature closes a circuit to operate sequence switch magnet 104 which advances the first selector sequence switch to position 8, this circuit including arms 118 and 110. Transmission circuits are closed in position 8 by the operation of relay 148, this relay as in the case of the busy call operating over the following circuit: uppermost armature and front contact of relay 103, arm 100 (position 8), relay 148, arm 118 (position 8), right armature and back contact of relay 105, arm 110 (position 8), to battery through the sequence switch magnet 104 which, as hereinbefore stated is marginal and does not operate in this circuit. Since the connector sequence switch is now in position 17, the operation of relay 148 closes a circuit for feeding talking current to the called line

over relay 106 at the first selector. This circuit includes the left winding of relay 106, arms 113 (position 8) of the first selector sequence switch and armature 155 and 5 front contact of relay 103, lower talking conductor, the called line, upper talking conductor, conductor 157, armature 191 and front contact of relay 148, right winding of relay 106 to ground. Talking current is 10 fed to the calling line over the windings of relay 101. The calling and called ends of the connecting circuit are inductively united but conductively separated by a pair of condensers 150 and 151 in accordance with well-known practice.

In the case of a successful connection, the release of the first and second selectors takes place as described in connection with a busy line, but the release of the connector is 20 slightly different, since it is now in position 17 instead of position 14. When ground is removed from the third wire 544 upon the release of the second selector, relay 500 in releasing connects ground at its inner right 25 armature to arm 502 (position 17) causing the sequence switch magnet to advance the sequence switch to position 22. In position 22 the circuit for the release magnet 512 is closed which in operating restores the 30 connector, and the off-normal springs 513 restore when the connector reaches its normal position and advance the sequence switch to position 1, as described in the case of a busy line.

35 *Interoffice calls.*

Considering now the case of a call extending through a plurality of offices. In tracing such a call Figs. 1, 2, 3, 4 and 5 40 are to be placed in the order named. When the first selector, (Fig. 1) is set opposite a level containing the outgoing trunk group desired and has seized an idle trunk therein, the relay 106 Fig. 1, in releasing as before 45 described extends the grounded third wire 144 to conductor 244, resulting in the operation of relay 201 of the repeater. Relay 106 also in releasing advances the first selector sequence switch to position 5, as described in the case of a local call. Relay 50 201 in operating closes a circuit from ground, relay 202, uppermost contact of relay 201, upper talking conductor to the interoffice incoming selector at the distant office, impulse relay 300 thereat returning 55 over the lower talking conductor, back contact of relay 207, lowermost front contact of relay 201 to battery through relay 203 causing relays 202, 203 and 300 to operate. 60 Relay 301 does not operate in this circuit since it is short-circuited over a back contact of relay 318. Relay 300 operates slow relay 302 over the arms 308 (position 1) of the incoming selector sequence switch. Relay 65 302 in turn operates relay 303. Relay

303 at its armature 325 connects the lower grounded armature of relay 300 to the slow relay 302 independently of the arms 308. These circuits are similar to those of the first selector. Relay 302 connects ground at 70 its upper armature through arm 304, (position 1) to the sequence switch magnet 305, causing the sequence switch to advance into position 2. When the calling subscriber operates his sender for the second digit of the 75 wanted number, the first retraction of the armature of relay 101 operates relay 105 as before described, which in attracting its armature locks itself over the following circuit: right winding of relay 105, back contacts of the primary and secondary magnets 80 107 and 111, outer left armature and front contact of relay 105, arms 113, (position 5) upper talking conductor armature 208 and front contact of relay 201 to ground at the 85 front contact of relay 202. A circuit is also closed by relay 105 to operate relay 205 as follows: right armature and front contact of relay 105, arm 118, (position 5) to the lower talking conductor over the conductors 147, 188 and armature 155 and front contact of relay 103, armature 209 and front contact of relay 201, relay 205, to free pole of battery. The operation of relay 205 90 opens the trunk loop to the distant office causing relay 202 of the repeater and the impulse relay 300 at the distant office to release and connecting ground to hold relay 203 operated for a purpose to be described. The release of relay 202 unlocks relay 105. 100 Relay 105 in retracting its right armature causes relay 205 to release which again closes the trunk loop to the distant office causing relays 202 and 300 to again energize. On the retraction of the upper armature of 105 the impulse relay 300, at the incoming selector when the loop circuit was opened by relay 205 of the repeater, stepping relay 306 operated over a circuit including the uppermost armature and front contact of relay 110 303, the upper back contact of relay 300, arm 315, (position 2) left back contact of relay 307, outer right back contact of relay 318, inner left armature and back contact of relay 311, armatures and back contacts of 115 secondary and primary magnets 310, 313, winding of relay 306 to battery.

Relay 306 in attracting its outer left armature locks itself over arms 308, (position 2) to the lowermost front contact of relay 303. 120 In attracting its inner left armature, relay 306 operates relay 307 in a circuit including the noninducting winding of relay 306. Relay 307 locks itself to ground at the retracted upper armature of impulse relay 300 over 125 the following circuit: left winding of relay 307, left winding of relay 306, conductor 352, outer left armature and left back contact of relay 318, left armature and front contact of relay 307, arm 315 (position 2). Relay 306 130

in attracting its right armature, connects ground over arm 314, to the primary magnet 310 causing the incoming selector to be moved one step. At the end of its stroke, magnet 310 opens the locking circuit of relay 306 as in the first selector selecting operations. Relay 306 opens the original circuit for relay 307, and this relay releases if relay 300 has pulled up. On completion of the series of 10 impulses, slow relay 309 which was operated in series with magnet 310 during the transmission of the impulses, releases, opening a circuit through sequence switch magnet 305 which was closed upon the initial operation 15 of relay 309, the circuit including conductor 344 and the lowermost armature and front contact of relay 303. The sequence switch advances to position 3, in which position relay 306 is operated over the arms 308, to 20 ground at the lower front contact of relay 300. Relay 306 operates relay 307 in this position. Relay 311 operates from ground supplied over arm 312 position 3 and the uppermost front contact of relay 303. Sequence 25 switch magnet 305 operates from ground on arm 304, position 3, causing the sequence switch to advance to position 4. Sequence switch magnet 305 is held energized in position 4 from ground through the arms 308, through the right front contact of relay 307 to the grounded third wire 344. Relay 306 is held up in position 4 over its outer left contact and inner right armature of relay 311. Relay 306 on position 4 operates secondary magnet 313 over outer right armature of relay 311, through arm 314 (position 4) to ground at the right front contact of relay 306 causing the selector switch to take one step connecting the test brush 320 to the 35 test multiple 321 of the first selector in the group. If this trunk is busy relay 307 will be held energized, after stepping relay 306 releases, as its circuit is opened by magnet 313, over a circuit including the noninductive winding of relay 306, outer left armature of relay 318, conductor 353, left armature and front contact of relay 307, arm 315 (position 4) to the grounded terminal 321. Relay 306 operates when magnet 313 closes its back 40 contact from the same ground on the busy terminal 321 and imparts an impulse to the magnet 313 to step the selector to the next trunk which is assumed to be idle. The circuit for relay 306 is as follows: battery, right 45 winding of relay 306, armatures and back contacts of magnets 313, 310, outer left armature and front contact of relay 311, conductor 326, outer left armature and back contact of relay 318, conductor 353, left armature and front contact of relay 307, arm 315 (position 4) to ground on the busy multiple 321. Assuming the second trunk to be idle relay 307 thereupon releases, preventing stepping movement and at its right armature extending the grounded conductor 344 to conductor 50 320 and to the seized trunk test terminal to render the same busy. The retraction of the right armature of relay 307 opens a circuit to the sequence switch magnet 305 which advances the sequence switch to position 5, as 55 in the case of the first selector. The operations of setting the second selector and connector need not be described since they are similar to those described for a local call, the impulses being transmitted from the impulse relay 300 of the incoming selector, instead of from impulse relay 101 of the first selector. Assuming therefore that the calling subscriber has transmitted the hundreds, tens and units impulses and that the line selected is busy, as hereinbefore described, the sequence switch of the connector advances from position 6 to 13 upon the termination of the units impulses, and the relay 500 is locked up, and at its inner right armature 60 grounds the upper talking conductor through these positions, arm 510 simultaneously grounding the lower talking conductor. The ground applied to the lower talking conductor over arm 510 closes a circuit leading back to the incoming selector passing to conductor 343, through contact 328 of relay 303, conductor 330, arm 314, (position 5) right armature and back contact of relay 306, arm 304, (position 5) 65 sequence switch magnet 305 to battery causing the interoffice incoming selector sequence switch to advance into position 6. In position 6, arms 308 of the incoming selector sequence switch again close a circuit to energize the sequence switch magnet 305, this circuit however being independent of the armature and back contact of said magnet. This circuit is the same as that traced including the lower talking conductor, but instead of passing by conductor 330 and over arm 314, it passes directly to arms 308 (position 6) and directly to the magnet 305. In position 6 relay 318 is operated over arm 312 to ground at the uppermost armature 70 and front contact of relay 303. Relay 318 in operating, locks itself to the grounded third wire 344 over its inner right armature. Relay 318 in attracting its outer right armature extends conductor 324 connected to the grounded upper talking conductor to the right winding of the ringing cut-off relay 317, over the left back contact of relay 307 and arm 315 (position 6). The ringing cut-off relay 317 thereupon operates and at its 75 inner right armature and front contact locks itself to the grounded third wire 344 over armature 346 and back contact of relay 319. When ground at the connector is removed from the lower talking conductor, as described, sequence switch magnet 305 releases and advances the sequence switch to position 7. Relay 317 being operated, at its outer right armature now closes a circuit over arm 314 (position 7) and the right 80 85 90 95 100 105 110 115 120 125 130

armature and back contact of relay 306, arm 304, magnet 305 to advance the sequence switch to position 8. In position 8, relay 319 is operated over arm 312 and the uppermost armature and front contact of relay 303. This relay attracting its outer armatures extends the upper and lower talking conductors of the second selector through to the corresponding conductors of the incoming selector. When the relay 318 operated as the incoming selector sequence switch moved to position 6, it opened at its inner left armature and back contact a shunt about the high resistance relay 301 resulting in the deenergization of a marginal relay 203 in the loop circuit leading back to the repeater and including relays 203, 300 and 202. The introduction of this high resistance in series in the trunk loop leading back to the originating office causes relays 202 and 203 thereat, as well as a relay 300 in the incoming selector circuit to release. Relay 301 in operating applies ground to conductor 340 leading to slow relay 302 to maintain relay 302, and consequently relay 303 energized after the circuit of relay 302 is opened at the lower armature and back contact of relay 300 to prevent premature release. When relay 203 in the repeater released, it connected ground through the left front contact of slow relay 204 to relay 206 which thereupon operated and locked itself to the grounded third wire 244. Relay 206 in attracting its armatures applies ground to the upper and lower talking conductors leading back to the first selector which causes the first selector to function in the same manner as it did in the case of a local busy line, that is to say, ground supplied from the lower back contact of relay 203, left front contact of relay 204, armature 210 and front contact of relay 206, lower talking conductor to the first selector circuit, front contact 155 of relay 103, conductors 188, 147, arm 118, (position 5) right back contact of relay 105, arm 110, sequence switch magnet 104 to battery. Magnet 104 advances the sequence switch of the first selector to position 6 in which position arms 113 connect magnet 104 directly to the lower talking conductor over the front contact 155 of relay 103. The magnet 104 holds up in this circuit, since this circuit does not include its self-interrupting contact. When the ground is removed from the lower talking conductor, magnet 104 deenergizes advancing the sequence switch to position 7. This ground is removed from the lower talking conductor when the relay 204 retracts its left armature. Relay 207 is deenergized due to the retraction of the right armature of slow relay 204 which in turn is deenergized due to the opening of its circuit at the front contact of marginal relay 203. Due to ground being present on the upper talking con-

ductor from lower armature and front contact of relay 207, and lower armature and front contact of relay 206, simultaneously with the ground on the lower talking conductor, this ground remaining until after the first selector sequence switch arrives in position 6, ringing cutoff relay 133 is operated in a circuit leading over the upper talking conductor, conductors 156, 160, armature 181 and front contact of relay 109, left armature and back contact of relay 106, arm 112, (position 6) right winding of ringing cutoff relay 133 to battery. This relay in attracting its inner right armature locks itself to the grounded third wire 144 and in attracting its outer right armature advances the sequence switch to position 8 as in the case of a local busy call. The circuit for advancing the sequence switch to position 8, leads over the outer right armature of relay 133, arm 118 (position 7) right armature and back contact of relay 105, arm 110, self-interrupting contact of magnet 104, winding of said magnet to battery. In position 8, relay 148 is operated over the following circuit: uppermost armature and front contact of relay 103, arm 100 (position 8) relay 148, arm 118 (position 8) right armature and back contact of relay 105, arm 110, magnet 104 to battery. Magnet 104 does not operate in this circuit but the relay 148 operates and connects the upper and lower talking conductors of the first selector to those of the trunk repeater circuit. When the relay 206 in the repeater operated, this relay in addition to grounding the upper and lower talking conductors with the results described, also at its uppermost armature opened the circuit of relay 201. This relay in retracting its armatures disconnects the repeating apparatus from the talking conductors and extends the talking conductors from the first selector directly through to the talking conductors of the incoming selector at the distant office. When the first selector sequence switch arrives in position 8, the following circuit is closed for the called supervisory relay 106, free pole of battery, left winding of said relay, conductor 170, arms 113, (position 8) conductor 188, front contact 155 of relay 103, lower talking conductor to the incoming selector of the distant office, high resistance relay 301, and bridged relay 300 thereat returning over the upper talking conductor, conductor 157, front contact of relay 148, right winding of relay 106 to ground.

Referring now to the connector circuit, it will be recalled that upon the setting of the connector on the line, the sequence switch of the connector advances from the third to the fourteenth position. If the line is busy, the relay 500 is locked up as has been described and consequently the sequence switch magnet circuit is opened at the inner

right armature and back contact of the relay 500. In position 14, busy tone current is transmitted over sequence switch arm 509 to the upper talking conductor and thence 5 to the calling line through the condenser 335 in the incoming selector circuit and condenser 150 in the first selector circuit, returning over the lower talking conductor through the lower winding of the relay 101 10 in the first selector circuit.

The calling subscriber upon hearing the busy tone replaces his receiver causing the release of relay 101 and consequently relays 102 and 103 in the first selector circuit 15 whereupon the first selector and the first selector sequence switch are restored as described in the case of a local call. The removal of ground from the third conductor 144 upon retraction of the lower armature 20 of relay 102 releases the relay 206 of the repeater, thus restoring the repeater apparatus to its normal condition. The release of the armature 155 of the relay 103 opens the loop circuit extending to the distant 25 office whereupon the relay 301 retracts its armature removing ground from conductor 340 thus releasing relays 302 and 303. Relay 303 in retracting its lowermost armature closes the following circuit for the release magnet 341 of the incoming selector; 30 free pole of battery, magnet 341, off-normal contact 342 to the lowermost back contact of relay 303. The retraction of the lowermost armature of relay 303 in removing 35 ground from the third wire 344 and consequently from the third wire 444 of the second selector causes this switch and its associated sequence switch to release in the manner described in the case of a local connection. 40 Arm 410 of the second selector sequence switch in restoring removes ground from the third wire 544 leading to the connector which likewise causes the restoration of this switch and the associated sequence 45 switch as described in the case of a local connection.

Assuming, however, that the selected line had been idle, in this event the relay 500 in the connector is not locked up while the sequence switch is passing from position 3 to 50 14 and consequently no ground is applied to the upper talking conductor since the inner right armature of relay 500 is resting on its back contact. Consequently when 55 the arm 510 passes off its thirteenth contact and removes ground from the lower talking conductor which ground has been holding up magnet 305 in position 6 of the incoming selector circuit, the incoming selector sequence switch does not pass directly 60 out of position 7 since the right armature of the ringing cutoff relay 317 is retracted owing to the fact that the right winding of this relay did not find a circuit leading 65 over the upper talking conductor. In posi-

tion 7 of the incoming selector sequence switch, ringing current is applied to the selected line over the following circuit: ringing generator, left winding of relay 317, arm 308 (position 7) armature 328 of relay 70 303, conductor 343 to the lower talking conductor of the second selector, arm 405, (position 6) arm 510, (position 17) through the bell of the selected station returning over the upper talking conductor, arm 509, (position 17) arms 403, (position 6) conductor 324, outer right armature and front contact of relay 318, left back contact of relay 307 to ground over the arm 315, (position 7). Relay 318 is energized in positions 6 and 7, 80 over arm 312 to the uppermost front contact of relay 303. This relay will have operated in position 6, opening the shunt about the high resistance relay 301 which resulted in the deenergization of the marginal relay 85 203 at the originating office and the release of this relay will have caused the advance of the first selector sequence switch to position 8 as described in the case of a busy connection. Ringing tone is transmitted to the calling line by induction through the windings of relay 317. When the called subscriber removes his receiver, the ringing cutoff relay 317 operates cutting off the ringing current and locking itself over its inner 90 right armature and a back contact of relay 319 to the grounded third wire. This relay in attracting its outer right armature advances the sequence switch to position 8 over arm 314, (position 7), right armature and 95 back contact of relay 306, arm 304, armature and back contact of the sequence switch magnet 305 to battery. The magnet 305 thereupon advances the sequence switch to 100 position 8. In this position relay 319 is operated over arm 312 to the uppermost front contact of relay 303. The energization of relay 319 extends the talking conductors of the incoming selector to the talking conductors of the second selector and causes the 105 operation of relay 307 over the following circuit: free pole battery, left winding of relay 307, conductor 350, arms 308, (position 8) armature 328 and front contact of relay 303 to the lower talking conductor and thence to the called line, returning over the upper talking conductor, conductor 345, armature and front contact of relay 319, right winding of relay 307 to ground. The attraction of the left armature of relay 307 110 closes the following shunt path about the high resistance relay 301: lower talking conductor 347 of the incoming selector, outer left front contact of relay 318, left front contact of relay 307, arm 315, (position 8) 115 conductor 348 to the lower talking conductor 347. The resultant increase in the current causes the relay 106 of the first selector of the distant office to energize which may be 120 used for supervision or for operating a 125 130

meter. When this high resistance relay is short-circuited relay 300 immediately operates closing a substitute ground to hold up relay 302 and consequently relay 303 after 5 the relay 301 has released. The parties may now converse, talking current for the calling subscriber's station being fed over the windings of relay 101, at the originating office and talking current for the called subscriber's station being fed over the windings of relay 307 at the distant office. The release of the connection upon the restoration of the receiver of the calling party to its switchhook takes place as described in the case of 10 a busy line.

Private branch exchange connections.

Considering now the operation of the system in selecting one of a number of lines 20 leading to the same station as for example a private branch exchange.

Referring now to Figs. 1, 4 and 6 and assuming that the second selector of Fig. 4 has seized a private branch exchange connector shown in Fig. 6, the operations from 25 this point will now be traced. It will be recalled that in the operation of the second selector when this switch seizes an idle trunk, arm 410 in position 5 applies ground to the test multiple 414 of the seized connector. Similarly, in Fig. 6, when the second selector of Fig. 4 seizes an idle P. B. X. connector, Fig. 6, arm 410 in position 5 applies ground to test multiples 600 of the 30 seized connector, and consequently to test wire 644, this ground being extended over arm 601, conductor 620 to release relay 602 which relay is similar to relay 500 in the connector. In attracting its inner right armature this relay advances the sequence switch to position 2 over arm 603 (in position 35 1). Relay 602 locks itself to the grounded third wire 644 over its inner left armature and front contact. Upon the operation of the sender by the calling party in transmitting the tens digit of the wanted number, the primary magnet 604 is operated over the lower talking conductor and arm 605 to step the connector in a primary direction to the desired group. The slow relay 606 at the termination of the impulses 40 releases, opening the circuit of the sequence switch magnet 607 which thereupon advances the sequence switch into position 3. In position 3 upon the operation of the sender by the calling party, impulses are transmitted to the secondary stepping magnet 608, in accordance with the units digit of the wanted number, which magnet steps 45 the switch and into engagement with the first trunk of the group leading to the desired private branch exchange. Upon the termination of this series of impulses, the slow relay 606 releases deenergizing sequence switch magnet 607 which advances 50

the sequence switch to position 4. Arm 601 in leaving position 3 opened the locking circuit of relay 602. Relay 602 in releasing its inner right armature advances the sequence switch magnet 607 over arm 603 advancing the sequence switch to position 5.

Assuming that the first trunk is busy or grounded, a circuit is closed to operate relay 610 over the arms 611, (positions 4 and 5), conductor 622 to grounded multiples 609, 616. Relay 610 closes the following circuit for relay 602: free pole of battery, relay 602, conductors 620, 619, outer left armature and front contact of relay 610, armatures and back contacts of magnets 608, 604, conductor 618, inner left armature and front contact of relay 610, conductors 617, 612, 613, arm 615, (position 5) and grounded multiple 616. Relay 602 in attracting its outer right armature closes the following circuit for magnet 608 to advance the connector to the next trunk: grounded outer right armature of relay 602, conductor 621, inner right armature and front contact of relay 610, conductors 624, 625, magnet 608, slow relay 606 to battery. Magnet 608 at the end of its stroke opens the circuit of relay 602 which releases its outer right armature deenergizing magnet 608. If the multiple 609 in this trunk is not grounded, relay 610 releases and the multiple 616 not being grounded, and relay 610 being inert, relay 602 cannot energize when the break in its circuit at the back contact of magnet 608 is closed. Relay 606 was energized during these impulses and upon releasing deenergizes the sequence switch magnet 607 whereupon the sequence switch is advanced to position 6, in which position and subsequent positions arm 615 grounds the test 105 multiples to render the seized trunk busy.

In position 6, relay 602 is energized over conductors 620, 628, arms 611 to ground. Relay 602 at its inner right armature and arm 603, (position 6) advances the sequence switch to position 7. Contacts 7 to 16 being grounded sequence switch moves immediately into position 17 and relay 602 being at this time inert connects ground at its inner right armature and back contact and arm 603 to the sequence switch magnet 607 which advances the sequence switch to position 19. In position 19, the relay 602 operates over the following circuit: free pole of battery, relay 602, conductors 620, 628, arms 611, position 19 to ground. Relay 602 in attracting its inner right armature advances the sequence switch over arm 603, into position 20, which is the talking position. Arm 605 in passing from positions 9 to 16 grounds the lower talking conductor leading back to the first selector just as in the case of a call to an ordinary subscriber as hereinbefore described with the same results. Talking current is fed to the calling and called 120 125 130

lines from the first selector as in the case of a connection to an ordinary local line.

When the calling party breaks down the connection, ground is removed from the third wire 644 which causes the release of relay 602 which upon being operated in position 19 locked up to the grounded third wire 644 over its inner left armature and arm 601. This relay in releasing its inner right armature closes a circuit including arm (position 20) and the sequence switch magnet advancing the sequence to position 22. In this position, the release magnet 629 is operated over the following circuit: free pole of battery, magnet 629, off normal springs 630, arms 611 (position 22) to ground. When the switch reaches its normal position and restores the off normal spring 630, a circuit is closed for the sequence switch magnet 607 as follows: magnet 607, its armature and back contact, arm 603, (position 22) conductor 631 to ground at the off normal springs whereupon the sequence switch advances to normal position.

Assuming now that all the private branch exchange trunks are busy, the connector will step over these trunks to the last trunk where it will stop, and result in a busy signal being given to the calling party. Terminals 609 and 616 of the last trunk are not connected together by a tie wire 621 as are the others. Consequently there is no ground present on multiple 609 of the last trunk even if it is busy. In this event, relay 610 releases and prevents further stepping by interposing a break in the circuit of relay 602 in retracting its outer left armature. The sequence switch is advanced from position 5 to position 6 by the release of the slow relay 606, just as in the case of a successful connection.

In position 6, relay 602 energizes over the following circuit: free pole of battery, relay 602, conductors 620, 628, arm 611 to ground. Relay 602 in attracting its inner right armature advances the sequence switch to position 7. Ground being present on the multiple 616, relay 602 is held up over the following circuit: free pole of battery, relay 602, inner left armature and front contact, conductor 632, arm 615, (position 7) to ground on the multiple 616. Contacts 7 to 16 of arm 603 being strapped together and being connected to ground, the sequence switch automatically passes to position 17. Relay 602 is not de-energized by the passing of the arm 615 out of its eighth position because an alternative circuit exists over conductor 633 and arm 601 to the grounded third wire 644. Due to the fact that relay 602 is operated, ground is transmitted from the inner right armature and front contact of said relay, conductors 634 and 635 to side switch arms 611 which extend this ground from positions 9 to 16 to the upper talking conductor. In these positions ground is being transmitted over arm

605 to the lower talking conductor to advance the first selector exactly as in the case of a busy connection to an ordinary subscriber. When the sequence switch reaches position 17, busy tone is transmitted over arms 611 to 70 the upper talking conductor and thence to the calling subscriber, as in the case of call to a busy ordinary line. The connector stays in position 17 until the calling party hangs up his receiver which results in the release 75 of the preceding switch as described in the case of a call to an ordinary line. The removal of ground from the third wire 644 due to the release of the second selector results in the release of relay 602. Relay 602 in re-80 tracting its inner right armature advances the sequence switch from position 17 to position 19. In position 19, relay 602 is operated over conductors 620, 628, arms 611 to ground and in attracting its inner right armature advances the sequence switch to position 20. In passing out of position 19, arms 611 open the circuit of relay 602 which in re-85 tracting its inner right armature advances the sequence switch into position 22 in which 90 position release takes place and sequence switch is restored as described in the case of a successful connection. In case the desired private branch exchange trunk group terminated in or belonged to a distant office the 95 connection would lead over a first selector of Fig. 1 and one or more selectors such as shown in Fig. 3.

Connections to an operator.

100

In case the calling subscriber desires a connection with an operator, he transmits impulses corresponding to a given digit which sets the first selector in operative relation to a group of trunks each terminating 105 in a jack 707 (Fig. 7) whereupon the selector automatically hunts over the group and picks out an idle trunk. One of these trunks is illustrated in Fig. 7. Assuming therefore that the set of impulses has been transmitted 110 and that the trunk hunting operation has taken place, the relay 106 in releasing its right armature extends grounded third wire 144 to the test multiple 700 of the selected trunk and thence to test wire 701, thus causing this 115 trunk to test busy to other selectors. Ground on conductor 701 is connected through the inner left armature and back contact of relay 703, left armature and back contact of relay 704 to the lower talking conductor 120 of the trunk and this ground is also connected over left outer armature and back contact of the relay 703 to the upper talking conductor. This causes the first selector sequence switch to move from posi-125 tion 5 into position 6, as described in the case of busy call to a local line. Ground upon lead 701 causes relay 702 to operate over a circuit including the right armatures and back contacts of relays 703 and 704. 130

Relay 702 on attracting its right armature connects ground through its left armature and front contact to relay 704 causing it to operate. Relay 704 locks to ground on lead 701 through its left-hand front contact and armature and inner left armature of relay 703. Relay 704 also connects ground from lead 701 to right-hand armature and front contact of relay 704 to calling lamp 705 which thereupon lights informing the operator of the arrival of a call. Relay 704 opens the circuit of relay 702 which is a slow release relay causing it to remove ground from lower talking conductor. This deenergizes sequence switch magnet 104 of the first selector which in releasing advances the first selector sequence switch out of position 6. It advances to position 9 in the following manner: Relay 133 which was operated when the first selector sequence switch reached position 6 due to the presence of ground on the upper talking conductor and thereupon locked up to the third wire 144 as is the case of a busy call, connects ground to arm 118, (position 7) right armature and back contact of relay 105, arm 110 (position 7) to the sequence switch magnet 104 causing the switch to advance to position 8. Ground on the upper talking conductor through lead 157, the lower back contact of relay 148, arm 118, (position 8) armature and back contact of relay 105, arm 110 to sequence switch magnet 104 advances the sequence switch to position 9. Relay 148 in position 8 cannot operate over arm 100 because it is shunted by conductor 157 to the grounded upper talking conductor. When the operator inserts her answering plug, relay 703 is operated from battery on the sleeve of the plug 706. Relay 703 removes ground from the upper talking conductor by attracting its left outer armature and also opens the circuit of lamp 705. Ground is connected to lead 701 to hold the trunk busy independent of the ground on the third wire 144 over the inner left front contact and armature of relay 703. Relay 106 in the first selector is now operated over the following circuit: free pole of battery, left-hand winding of relay 106, lead 170, arms 113, (position 9) armature and front contact 155 of relay 103, lower talking conductor to ground on the tip of plug 706. The relay 106 connects the grounded release trunk 144 over its right-hand armature and front contact, arm 118, (position 9) right-hand armature and back contact of relay 105, arm 110, back contact and armature of sequence switch magnet 104 causing the sequence switch to advance into position 10. In passing out of position 9 arms 113 cause the release of relay 106. Relay 186 is operated now over the following path: ground on the upper armature and front contact of relay 103 arm 100, (position 10) relay 186 to battery. The operation of relay 186 extends the talking conductors from the line switch directly to the first selector brushes opening the current feeding bridges at the first selector. Relay 186 locks over its upper armature and front contact to release conductor 144. The relay 101 is deenergized upon the operation of relay 186 causing relays 102 and 103 to release but due to the break in the circuit of release magnet 135 by the attraction of the lower armature of relay 186, the selector is held in its set position.

The line switch is also held set due to the previous placing of a ground on the third wire 144 from the grounded third wire 701, this ground being extended to the wire 144 over the right retracted armature of relay 106. Thus the control of release is with the operator. Talking current is fed to the calling and called lines from the battery in the operator's cord circuit. When the operator removes plug 706, relay 703 releases removing ground from conductor 701 which in turn causes relay 186 in the first selector to release. Release magnet 135 is now operated over the off-normal springs 136, lowermost armature and back contact of relay 186, and lowermost armature and back contact of relay 103 now inert. Upon the restoration of the selector, the off-normal springs 136 restore whereupon the following circuit is closed to advance the sequence switch out of position 10: free pole of battery, magnet 104, arm 110, (position 10) springs 136, lowermost armature of relay 186 and lowermost armature of relay 103 to ground. The sequence switch automatically passes to normal position. Thus the apparatus is all restored ready for the next call. The removal of ground from the third wire 144 by the removal of the plug causes the line switch to restore in a well-known manner.

From the foregoing it will be seen that the invention provides an interoffice repeating system which will permit of the accurate setting of automatic switches irrespective of the length of trunks, within commercial transmission limits, and irrespective of the number of trunks and lines over which the connection is built up, and will accurately operate under a wide range of variations, obviating delicate adjustments of the finger wheel, relays or mechanism of the switches.

In the system of this invention, the number of impulses transmitted by the finger wheel or dial per second may be materially increased over systems now in use without sacrificing accuracy in the setting of the switches and without increasing cost of maintenance or first cost of the dials.

In systems now in use, the ratio of the break to the make period of the dial must

be maintained within narrow limits, which results in high maintenance as well as first cost. With the arrangement of this invention, a wide range of variation between the 5 ratio of the make and break periods of the dial is permissible since the period of current flow in the stepping magnet is not dependent upon the break period of the dial.

Consideration of the circuits show that in 10 order to set the switches at the originating office and those switches of the offices through which the call progresses, it is only necessary that the impulse relay at each office retract its armature for a period long 15 enough to permit the associated stepping relay 105 to attract its armature whereupon it locks up to the already energized trunk relay 202 and starts the cycle of operations. On the other hand, it is only necessary that 20 the impulse relay at each office hold its armature attracted for a period long enough to permit the associated relay 106 to release its armature to again connect the stepping relay to the back contact of the impulse 25 relay. The function of the relay 106 is to prevent the stepping relay from initiating a second cycle of operations for one and the same retraction of the armature of the impulse relay. The stepping relay may be 30 arranged to cooperate in .005 of a second and the relay 106 to release in .003 of a second. In commercial practice dials transmit about 10 impulses per second which gives about .1 of a second from break to break.

35 If line conditions are such as to cause the impulse relay 101 to be retracted for very short intervals, the associated relay set nevertheless goes through its cycle of operations and positively releases the succeeding impulse relay once for each such retraction, which in turn initiates a cycle of operations of its relay set to positively release the succeeding impulse relay and so on.

If, on the other hand, the line conditions 45 are such as to cause the impulse relay 101 to be retracted for long intervals the associated relay set operates in the same manner and restores, the relay 106 releasing a fraction of a second after the impulse relay 50 finally pulls up its armature, this relay reconnecting the stepping relay to the back contact of the impulse relay, for the next retraction. By virtue of the present invention therefore it will be readily appreciated 55 that margins are provided which are more than ample to meet practically any line conditions which may be encountered.

In actual practice a short impulse transmitted to the stepping magnet of a selector 60 due to the impulse relay being deenergized for a period substantially shorter than the break period caused by the sender, will sometimes cause the selector to be elevated two steps instead of one. The reason for 65 this is that a locking projection is provided

on the selector against which the driving pawl abuts at the end of its stroke, this projection being so formed as to force the pawl into the ratchet and lock it, if the pawl gets a full step. If the impulse is too short, it ceases before the pawl reaches the locking projection and the deenergization of the magnet allows the pawl to drop back but the momentum of the shaft is such as to carry it up high enough for the holding 70 pawl to engage the second tooth. This will readily be understood from inspection of Fig. 33 of Patent 815,176 of March 13, 1906, see lines 109 to 119 of page 4 thereof.

By virtue of the present invention this 75 cannot occur since the stepping relay operates on a very short impulse and then locks itself to the back contact of the step magnet. In its operated position it closes the stepping circuit and this impulse does not 80 terminate until the driving pawl reaches the end of its stroke when it is forced by said locking projection into the tooth positively locking the shaft. Then the impulse is cut-off by the stepping relay being unlocked due 85 to the driving pawl having reached the required position.

On the other hand if the impulse relay 90 is deenergized for a period substantially longer than the break period caused by the 95 sender this will sometimes cause the selector to be elevated to the level below the one desired. The reason for this is that the next break period arrives before the impulse relay armature has been attracted long enough 100 to allow the stepping magnet winding to discharge and consequently an impulse is lost. In the circuit arrangement of this invention, this cannot occur inasmuch as the stepping relay is deenergized under the sole 105 control of the stepping magnet armature which in turn in releasing opens the circuit of the magnet, and the circuit characteristics are such that this always occurs in time to 110 permit the magnet winding to discharge and be ready for the next impulse when the impulse relay again retracts its armature.

Claims to other features than the repeating system claimed herein will be presented 115 in separate applications.

What is claimed is:

1. In a machine switching telephone exchange system, telephone lines, offices where-in said lines terminate, trunk lines interconnecting said offices, means at each office for producing a cycle of operations, an impulse relay at each office adapted upon the movement of its armature in one direction to start said means in operation, circuits each including a trunk from one office to the next including the impulse relay thereat, the electrical condition of which is changed by said means while it is going through a cycle of operations, the cycle of operations of each of said means when initiated upon 120
- 125
- 130

operation of the corresponding impulse relay being independent of the subsequent movement of the armature of said impulse relay in the other direction, and automatic switches controlled by said impulse relays for building up the connection.

2. In a machine switching telephone exchange system, telephone lines, offices wherein said lines terminate, trunk lines interconnecting said offices, means at each office for producing a sequence of operations, an impulse relay at each office adapted upon its deenergization to start said means in operation, circuits each including a trunk from one office to the next including the impulse relay thereat opened by said means while it is going through a cycle of operations, the cycle of operations of each of said means when initiated upon deenergization of the corresponding impulse relay being independent of the subsequent energization of said relay, and automatic switches controlled by the impulse relays for setting up the connection.

3. In a machine switching telephone exchange system, telephone lines, offices wherein said lines terminate, trunk lines interconnecting said offices, automatic switches included in said trunk lines, a sender to control said switches to build up a connection between a calling and a called line over said trunk lines and leading through a number of offices, an impulse relay at each office associated with the trunk circuit, and means at each office for producing a cycle of operations and when set in operation by the deenergization of the corresponding impulse relay opens the circuit leading to the next office for a period of time independent of the subsequent energization of the corresponding impulse relay, said means completing its cycle of operations, however, before the subsequent retraction of the armature of the impulse relay.

4. In a machine switching telephone exchange system, telephone lines, offices wherein said lines terminate, automatic switches at each office, a sender, an impulse relay at each office, means at each office when set in operation by the retraction of the armature of the corresponding impulse relay to transmit an impulse to the switches in the associated office, and also upon the seizure of a trunk leading to the next office likewise when set in operation upon the retraction of the armature of the impulse relay causes a circuit change in the circuit of the impulse relay of the next office, the duration of said circuit change being independent of the subsequent attraction of said armature, and automatic switches adapted to be set by the impulses so produced.

5. In a machine switching telephone exchange system, telephone lines, offices wherein said lines terminate, senders for said lines,

trunk lines and automatic switches over which a connection may be built up between lines in different offices, a repeating device associated with the originating end of each trunk, an impulse relay for operating the same, said device when operated upon the retraction of the armature of said impulse relay being arranged to open the trunk circuit, the duration of such break period being independent of the subsequent attraction of said armature.

6. In a machine switching telephone exchange system, telephone lines terminating in different offices, senders for said lines, trunk lines and automatic switches over which a connection may be built up between lines in different offices, a repeating device associated with the originating end of each trunk, an impulse relay adapted upon the retraction of its armature to cause said device to open the trunk circuit, the duration of such break period being independent of the subsequent attraction of said armature and said device being so arranged that it will complete its cycle of operations and return to normal, reclosing the trunk circuit, prior to the next retraction of the said armature.

7. In a machine switching telephone exchange system, telephone lines terminating in different offices, senders for said lines, trunk lines and automatic switches over which a connection may be built up between lines in different offices, a repeating device associating with the originating end of each trunk, local stepping circuits for the magnets of said switches, an impulse relay at the originating office in circuit with the sender adapted to set the repeating device thereat in operation once for each retraction of its armature to cause said device and the repeating devices of the offices beyond to transmit to the magnets of the switches in the last office impulses equal in number to those transmitted by the sender but whose duration is controlled solely by the repeating device of the last office, said impulses being independent of the subsequent attractive movement of said armature.

8. In a machine switching telephone exchange system, telephone lines, offices wherein said lines terminate, senders for said lines, trunk lines extending between said offices, automatic switches for building up connections between lines in distant offices and including said trunk lines, a repeating device for each interoffice trunk adapted to produce therein interruptions corresponding in number to those produced by the sender, the duration of said interruptions being solely controlled by the corresponding repeating device, automatic switches adapted to be set under control of the interruptions so produced, and means operated upon the setting of the connector upon the desired line for removing said repeating devices from connec-

tion with the talking conductors of the trunks.

9. In a machine switching telephone exchange system, telephone lines, offices where in said lines terminate, a connection extending from a calling line in one office and including the sender of such line and through switches at a plurality of offices to the office preceding that wherein a called line terminates, a selector in said intermediate office adapted to be set under the control of the sender to seize a trunk leading to the office wherein the called line terminates and terminating in an incoming selector thereat, and 10 a set of repeating relays in said trunk adapted to be operated under the control of the sender to produce in said trunk interruptions corresponding in number to those produced by the sender, the duration of said interruptions 15 being solely controlled by said repeating relays, automatic switches adapted to be set under control of the interruptions so produced to connect with the called line, and means automatically operated when connection is made to the called line for removing 20 said repeating relays from said trunk.

10. In a telephone system, a telephone line, a trunk line, means for extending said telephone line to said trunk line, a repeating device, an impulse relay, means including a sender for producing impulses in said telephone line to operate said impulse relay, said relay being adapted upon each movement of its armature in one direction to start said repeating device in operation to produce in said trunk circuit changes corresponding in number to those produced in the telephone line, the duration of said changes being independent of the subsequent movement of said 25 armature in the other direction, and an automatic switch in which said trunk terminates adapted to be set by the circuit changes so produced.

11. In a telephone system, a circuit, a second circuit, a sender for said first circuit, repeating means associated with said second circuit, an impulse relay in said first circuit intermittently operated by said sender, a circuit closed upon each deenergization of 30 said impulse relay to start said repeating means in operation to interrupt said second circuit, an impulse relay at the distant end of the second circuit deenergized thereby, an automatic switch, and an impulse circuit 35 closed by the deenergization of said impulse relay and including the stepping magnet of said switch, the duration of the interruption of the second circuit and consequently of the impulse imparted to said magnet being independent of the subsequent energization 40 of the impulse relay in said first circuit, but terminating before said impulse relay again retracts its armature due to the succeeding break caused by the sender in 45 the first circuit.

12. In a telephone system, a telephone line, a trunk line, an automatic switch in which said trunk line terminates, means for extending said telephone line to said trunk line, a repeating relay set in said trunk line, 70 an impulse relay, means including a sender in said telephone line to intermittently operate said impulse relay, a circuit closed upon each deenergization of said impulse relay adapted to start said repeating relay set in operation to interrupt said trunk circuit, an impulse relay at the distant end of the trunk deenergized thereby to produce an impulse for controlling the stepping magnet of said automatic switch, the duration of the 80 interruption of said trunk circuit by said repeating relay set being independent of the subsequent energization of the first impulse relay by the sender in the line circuit.

13. In a telephone system, a telephone line, a trunk line, an automatic switch in which said trunk line terminates, means for extending said telephone line to said trunk line, a repeating relay set in said trunk line, 85 an impulse relay, a sender in said telephone line for intermittently operating said impulse relay and a circuit closed upon each deenergization of said impulse relay adapted to start said repeating relay set in operation to interrupt said trunk circuit, an impulse 90 relay at the distant end of the trunk deenergized thereby to transmit an impulse to the stepping magnet of said automatic switch, the interruption of said trunk circuit by said repeating relay set being independent of the subsequent energization of the impulse relay in the line circuit, the trunk circuit being closed by said repeating relay set prior to the next retraction of the armature of the impulse relay in circuit 95 with the sender.

14. In a telephone system, a telephone line, a trunk line, an automatic switch in which said trunk line terminates, means for extending said telephone line to said trunk line, and a repeating relay set in said trunk line, an impulse relay, means including a sender in said telephone line for producing impulses therein intermittently to operate said impulse relay, a circuit closed upon each deenergization of said impulse relay adapted to start said repeating relay set in operation to interrupt said trunk circuit, an impulse relay at the distant end of the trunk deenergized thereby to transmit an impulse 110 to the stepping magnet of said automatic switch, the interruption of said trunk circuit by said repeating relay set being independent of the subsequent energization of the impulse relay in the line circuit, and 115 means for automatically removing said relay set from connection with the trunk 120 when the connection is built up.

15. In a telephone system, a telephone line, a trunk line, an automatic switch in 125

- which said trunk line terminates, means for extending said telephone line to said trunk line, a repeating relay set in said trunk line, an impulse relay, means including a sender 5 in said telephone line for producing impulses therein to intermittently operate said impulse relay, a circuit closed upon each de-energization of said impulse relay adapted to start said repeating relay set in opera- 10 tion to interrupt said trunk circuit, an impulse relay at the distant end of the trunk deenergized thereby to transmit an impulse to the stepping magnet of said automatic switch, the interruption of said trunk circuit by said repeating relay set being independent of the subsequent energization of the impulse relay in the line circuit, the trunk circuit being closed by said repeating relay set prior to the next retraction of the 15 armature of the impulse relay in circuit with the sender, and automatic switches each po- sitioned by a set of impulses transmitted by the sender and thus relayed by the repeating relay set.
- 20 16. In a machine switching telephone exchange system, telephone lines, an automatic switch for interconnecting the same, a circuit including a sender and an impulse relay, and a circuit closed upon each movement of the impulse relay armature in one direction 25 and including a relay which when operated in this circuit locks itself in a circuit including the back contact of the stepping magnet of said switch, said relay in oper- ating also closing a circuit to operate said magnet to step said switch.
- 30 17. In a machine switching telephone exchange system, telephone lines, an automatic switch for interconnecting the same, a circuit including a sender and an impulse relay, and a circuit closed upon each movement of the impulse relay armature in one direc- 35 tion and including a relay which when operated in this circuit locks itself in a circuit including the back contact of the stepping magnet of said switch, said relay in oper- ating also closing a circuit to operate said magnet to step said switch, the said locking circuit being opened at the completion of the 40 stroke of the armature of said stepping magnet.
- 45 18. In a telephone system, a telephone line, an automatic switch, means for connecting said line to said switch, an impulse relay for said switch, a stepping relay for said switch, a sender for interrupting the circuit of said impulse relay a number of times corresponding to the digit transmitted, a circuit including a back contact of 50 said impulse relay and said stepping relay, a circuit for operating said magnet closed by said stepping relay, and a locking circuit for said stepping relay independent of the back contact of said impulse relay and including a back contact of said stepping 55 relay.

magnet whereby the magnet is not deener- gized by the subsequent attraction of the im- pulse relay armature but under control of its own armature.

19. In a telephone system, a telephone line, an automatic switch, means for connecting said line to said switch, an impulse relay for said switch, a stepping relay for said switch, a sender for interrupting the circuit of said impulse relay corresponding to the digit transmitted, a circuit including a back contact of said impulse relay and said stepping relay, a circuit for operating said magnet closed by the stepping relay, a locking circuit for said stepping relay independent of the back contact of said impulse relay and including a back contact of said stepping magnet, whereby the magnet is not deenergized by the subsequent attraction of the relay armature but under control of its own armature, and means for opening said locking circuit prior to the subsequent re- traction of said impulse relay armature.

20. In a machine switching telephone exchange system, telephone lines, automatic switches for interconnecting the same, a circuit including a sender and an impulse relay, a circuit closed upon each retraction of the armature of said impulse relay and including a relay which when operated in this circuit locks up to a back contact of the stepping magnet of the automatic switch, said relay in operating also closing a circuit to operate said magnet to step said switch, and means for opening the said locking circuit at the completion of the stroke of said magnet armature, whereby the duration of the impulse imparted to the magnet is independent of the period during which the impulse relay armature rests on its back contact.

21. In a machine switching telephone exchange system, telephone lines, automatic switches for interconnecting the same, a circuit including a sender and an impulse relay, a circuit closed upon each retraction of the armature of impulse relay and including a relay which when operated in this circuit locks up to the back contact of the primary stepping magnet of the automatic switch and also closes a circuit including said magnet, and means for opening said locking circuit at the completion of the stroke of said magnet, whereby the duration of the impulse imparted to the magnet is independent of the period during which the impulse relay armature rests on its back contact, and a relay operated by the stepping relay adapted to interpose a break in the energizing circuit of the stepping relay, the said relay deenergizing upon the subsequent energization of the impulse relay.

22. In a machine switching telephone exchange system, telephone lines, offices wherein said lines terminate, a trunk circuit

- interconnecting said offices, a set of repeating relays at the originating office, an impulse relay 300 at the succeeding office, a loop circuit closed upon the seizure of the 5 trunk and including said repeating relay set and said impulse relay, an impulse relay 101 and a stepping relay 105 at the originating office, a subscriber's line including said impulse relay 101 and having a dial thereat 10 for intermittently operating the same, each deenergization of impulse relay 101 being adapted to operate stepping relay 105, means whereby said stepping relay 105 in energizing operates one of the relays 205 of said 15 repeating relay set to interpose a break in the trunk circuit leading to the next office to deenergize the impulse relay 300 thereat, and to deenergize a second relay 202 of such repeating set, the deenergization of relay 202 causing the release of said stepping relay 105, which in turn causes the release of said relay 205 of the repeating set, which in releasing again closes the trunk circuit to the succeeding office, a stepping relay 306 20 thereat, said impulse relay 300 at the succeeding office in releasing energizing said stepping relay 306 and automatic switches adapted to be set by said stepping relay 306.
23. In a telephone system, a circuit including an impulse relay and a sender, a trunk circuit, an automatic switch terminating therein, an automatic switch adapted to select said trunk circuit under control of said sender, an impulse repeater in said 30 trunk operated on seizure of said trunk to close a loop circuit including the trunk conductors and the stepping relay of said first mentioned automatic switch, a circuit closed upon each movement of the armature of said 35 impulse relay in one direction, a locking relay included in said circuit, a locking circuit for said relay closed upon its energization and including a contact of a relay of said repeater, the actuation of said locking relay 40 operating another relay of said repeater to open said loop circuit and said locking circuit.
24. In a telephone system, a circuit including an impulse relay and a sender, an 45 automatic switch terminating therein, an automatic switch adapted to select said trunk circuit under control of said sender, a repeater in said trunk having a relay operated in a loop circuit including a relay of 50 said repeater and the stepping relay of said first mentioned automatic switch, a circuit closed upon each retraction of the armature of said impulse relay and including a locking relay which when operated in said circuit locks itself in a circuit including a front 55 contact of said operated repeater relay, said locking relay operating a stepping relay in said repeater to open said loop circuit.
25. In a telephone system, telephone lines, 60 an automatic switch, a circuit including a 65 sender and an impulse relay, a circuit closed upon each movement of the impulse relay armature in one direction and including an impulse repeating relay which when operated locks itself in a circuit including the 70 normal contact of the stepping magnet of said switch, said latter relay in operating also closing a circuit to operate said magnet, other automatic switches adapted to be selected by said first switch, electromagnetic changeover means at said first switch actuated on the selection of a second switch thereby for operatively associating said impulse repeating relay directly with the stepping magnet of said second switch, automatic switches adapted to be selected by said second switch, and electromagnetic changeover means at said second switch and actuated on the selection of an idle third switch thereby for operatively associating said impulse repeating relay directly with the stepping magnet of said last mentioned switch. 75
26. In a telephone system, telephone lines, an automatic switch, a circuit including a sender and an impulse relay, a circuit closed upon each retraction of the impulse relay armature and including an impulse repeating relay which when operated locks itself in a circuit including the normal contact of the stepping magnet of said switch, said latter relay in operating also closing a circuit to operate said magnet, other automatic switches adapted to be selected by said first switch, electromagnetic changeover means at said first switch actuated on the selection of a second switch thereby for operatively associating said impulse repeating relay directly with the stepping magnet of said second switch, automatic switches adapted to be selected by said first switch, and electromagnetic changeover means at said first switch actuated on the selection of a second switch thereby for operatively associating said impulse repeating relay directly with the stepping magnet of said second switch, automatic switches adapted to be selected by said second switch, and electromagnetic changeover means at said second switch and actuated on the selection of an idle third switch thereby for operatively associating said impulse repeating relay directly with the stepping magnet of said last mentioned switch. 80
27. In a telephone system, telephone lines, senders therefor, an automatic switch, trunk lines, automatic switches in which said trunks terminate, an impulse repeating relay at the first of said switches, an impulse relay at said switch in circuit with the calling line sender, a circuit closed upon each movement of the armature of said impulse relay in one direction to operate said impulse repeating relay, a locking circuit for said repeating relay including a normal contact of the stepping magnet of said first switch, a circuit closed by said repeating relay and including said magnet, means for causing said switch to test for and seize an idle trunk, electromagnetic changeover means thereupon actuated for preparing circuits for operating the switch in which said trunk terminates, a circuit closed upon each 85

movement of the armature of said impulse relay in one direction in responding to the next set of impulses from said sender to operate said impulse repeating relay, a locking circuit for said repeating relay including contacts of said changeover means and a normal contact of the stepping magnet of

the second switch, and a circuit closed by said repeating relay and including the said second switch stepping magnet. 10

In witness whereof, I hereunto subscribe my name this 30th day of December A. D., 1919.

WARREN W. CARPENTER.
